Bynum, Robbins & Hamelton

UNITED STATES PATENT OFFICE.

WILLIAM F. HART, OF PITTSBURGH, PENNSYLVANIA, ASSIGNOR TO VERONA TOOL WORKS, OF PITTSBURGH, PENNSYLVANIA, A CORPORATION OF PENNSYLVANIA.

RAIL BOND.

Application filed September 22, 1922. Serial No. 589,790.

To all whom it may concern:

Be it known that I, WILLIAM F. HART, a citizen of the United States, residing at Pittsburgh, Allegheny County, State of Pennsylvania, have invented a new and useful Improvement in Rail Bonds, of which the following is a full, clear, and exact description.

The present invention relates broadly to railway track bonds and more particularly to bonds having generally resilient characteristics and adapted to be clamped in position between the webs of the rail ends to be bonded and the fish plate for the rail joint.

It has heretofore been proposed to construct rail bonds of this general character of resilient material having rail web engaging points and curved either longitudinally, transversely, or both, to increase the strength of the bond and insure a better contact between the ends thereof and the rail webs. In most cases, however, such bonds have not been constructed with regard to economy of manufacture and weight of material. This is illustrated by reference, for example, to the patent to Marsellis No. 588,771 of August 24, 1897. In view of the duty which bonds of this nature perform, it is not essential that they contain a large amount of material so long as a good contact with the rail ends is provided.

By the present invention there is provided a rail bond of minimum cost and weight and of such construction that an efficient track circuit for the operation of signals is insured.

In the accompanying drawings I have shown, for purposes of illustration only, certain embodiments of the present invention, it being understood that these drawings do not define the limits of this invention as changes may obviously be made in the construction and operation disclosed without departing from the spirit or scope of my broader claims.

In the drawings:

Figure 1 is a sectional view through a portion of a rail joint showing one form of track bond in position; Figure 2 is a side elevation of the construction illustrated in Figure 1, the fish plates being removed and the clamping bolts being in section; Figure 3 is a plan view illustrating one

manner of producing bonds of the construction shown in Figures 1 and 2;

Figures 4, 5 and 6 are views, corresponding to Figure 3, illustrating slightly modified forms of bonds;

Figure 7 is a transverse sectional view through the bond illustrated in Figures 1 and 2, and

Figure 8 is a longitudinal sectional view through the bond of said figures.

Referring more particularly to Figures 1, 2, 7 and 8 of the drawings, there is shown a portion of a track point comprising rail sections 2 and 3, the joint between which is bridged in usual manner by fish plates 4.

Between the center bolts 5 which hold the fish plates in position there is usually sufficient room for the insertion of a track bond 6 constructed in accordance with this invention. Such a bond may comprise a body of resilient material curved either longitudinally, transversely, or both, the latter construction being illustrated in these figures. The ends of the bond are formed to provide a plurality of triangularly shaped points 7, which points are adapted to cut through the scale or rust on the rail webs and form therewith good electrical contact.

After a bond is placed in position between the center plates, it will be apparent that as the fish plates are drawn into position, they will press upon the center portion of the bond and thereby cause the points 7 to forcibly penetrate any coating on the rail webs.

In Figure 3 there is illustrated one manner of producing the bonds illustrated in Figures 1, 2, 7 and 8. Due to the shape of the bonds, they may be conveniently formed by stamping from a suitable body of material. The shape of the bonds is also such that a maximum number of bonds may be produced from a sheet of given size, this result being obtained by reason of the fact that the bonds are of gradually decreasing width toward the points whereby an interlocking relationship exists between adjacent blanks. During the stamping operation, it will be apparent that the bonds may be given the curvature which is desired in the finished article.

In Figure 4 there is illustrated a bond 6^a having triangularly shaped rail engaging points 7^a. In this construction there is

provided a single point at one end of the bond and a pair of points at the opposite end.

Figure 5 illustrates another modification in which the bond 6^b is formed with a single point 7^b at each end, while in Figure 6 there is shown a bond 6^c of generally diamond shape.

All of the bonds illustrated herein are of such nature that they may be curved either in one direction only or in both directions, as any curvature will be sufficient to bring the rail engaging points into position where they will be operative as desired. In each case also the points are located adjacent the most distant extremities of the body, and the body is of minimum width adjacent these points, the body being of gradually decreasing width toward the points. This facilitates the formation of the bonds and enables the blanks to be marked off in overlapping relationship whereby all of the metal stock is conserved and utilized.

The advantages of the present invention arise from the provision of a rail track bond

of minimum weight coupled with maximum strength and efficiency.

I claim:

1. A rail bond formed of spring sheet material, having curved triangularly shaped rail engaging points extending longitudinally therefrom and in opposite directions, said points being so shaped and positioned that the portions cut away to form the points on the bond blanks, when blanking from a sheet, will form the points of other bond blanks.

2. A rail bond formed of spring sheet material, having triangularly shaped rail engaging points curved in two directions and extending longitudinally therefrom in opposite directions, said points being so shaped and positioned that the portions cut away to form the points of the bond blanks, when blanking from a sheet, will form the points of other blanks.

In testimony whereof I have hereunto set my hand.

WILLIAM F. HART.
